UNITED STATES PATENT OFFICE

137,667

DESIGN FOR AN AIRPLANE

Othmar F. Maycen, New York, N. Y.

Application August 17, 1942, Serial No. 107,951

Term of patent 7 years

(CL. D71—1)

To all whom it may concern:

Be it known that I, Othmar F. Maycen, a citizen of the United States, residing at the Borough and county of Bronx, city and State of New York, have invented a new, original, and ornamental Design for an Airplane, of which the following is a specification, reference being had to the accompanying drawings, forming part thereof wherein—

Figure 1 is a top plan view of the airplane showing my new design;

Figure 2 is a front elevational view of the said airplane;

Figure 3 is a side elevational view of the airplane depicted by Figure 1; and

Figure 4 is a top perspective view of the airplane in flight.

I claim:

The ornamental design for an airplane, substantially as shown.

OTHMAR F. MAYCEN.
